his attorney.

UNITED STATES PATENT OFFICE.

HERMANN WERNER, OF GENEVA, SWITZERLAND.

SHAVING DEVICE.

1,241,798.

Specification of Letters Patent.

Patented Oct. 2, 1917.

Application filed September 19, 1916. Serial No. 120,998.

To all whom it may concern:

Be it known that I, HERMANN WERNER, cutler, a citizen of Switzerland, residing at Geneva, Canton of Geneva, in the Confederation of Switzerland, have invented certain new and useful Improvements in and Relating to Shaving Devices, of which the following is a specification.

The object of the invention is the provision of an improved shaving device somewhat similar to the well known barber's shearing machines, but constructed so as to shave evenly to the surface of the skin without the need of soap, and with the same degree of perfection as is obtained with a common razor, or with a so-called safety-razor.

In the well-known shearing-machines as commonly constructed there is a stationary protecting-comb the outer face of which when in use bears against the skin, while the cutting-comb moves on the inner face of the said protecting-comb.

In my improved shaving device to the contrary it is the cutting-comb which is made stationary and is adapted with its outer hollow face to bear against the skin, while the protecting-comb moves on the inner side of the said cutting-comb, and both combs work together like a pair of scissors upon the beard to be cut.

In the drawing:

Figure 1 is a perspective view of the top of my improved shaving-device.

Fig. 2 is a side elevation of the same from the right to the left.

Fig. 3 is a perspective view of the bottom of the device with the cutting-comb removed.

Fig. 4 represents separately a face-view of the fixed cutting-comb which is adapted to contact with the skin.

Fig. 5 represents the rear side of said comb.

Fig. 6 shows the bolt or pivot for securing the handles to one another and to the combs.

Fig. 7 shows on a larger scale the two combs in cross-section and in working position.

Fig. 8 is a top-view of the movable protecting-comb, and

Fig. 9 is a view of the opposite face of the same.

In the drawing, *a* and *b* designate the handles of the shaving device. The handle *a* is provided with a cylindrical casing *a'* containing a helical spring for returning the

movable comb into its initial position after each operation of the handles *a*, *b* by the attendant. The handle *a* is provided with three projections *a²*, *a³* and *a⁴* adapted to receive and act as rests for the fixed cutting-comb *c*. This handle *a* is further provided with an edge or rib *a⁵* engaging with a corresponding groove *d¹* of the movable protecting-comb *d* for guiding the same in the reciprocating movements thereof.

The handle *b* is fitted with a screw *b¹* acting against the spring contained in the casing *a'* to normally maintain the handles in their spread positions as shown. The handle *b* is also provided with a tooth *b²* for engaging a recess *d²* in the movable protecting comb *d* in order to cause a reciprocating movement of the comb *d* by drawing the handles toward one another and releasing the same.

I also employ a bolt *e*, see Fig. 6 which acts as a pivot for joining the handles *a* and *b* together and securing the combs *c* and *d* to said handles. The pressure of the parts on one another is made yielding by means of a bent washer *e¹* which maintains the combs in working contact with each other and at the same time permits the comb *d* to move on the comb *c* without undue friction.

As shown in Fig. 7, the stationary cutting-comb *c* is provided with a hollow face *c'* which makes its use possible and practical on the neck and cheeks; and it is to be noted that the teeth of the movable protecting-comb *d* project appreciably beyond those of the comb *c* so as to prevent cutting into the skin during the shaving operation.

Furthermore the handles *a* and *b* are shaped in such a way that the operator may easily apply the blade *c* to any part of the neck or face, which, so far as I am aware is not possible with the shearing-machines heretofore in use.

I claim as my invention:

1. A shaving instrument comprising a pair of pivoted handles, a stationary cutting comb, a guard member having teeth which project materially beyond the teeth of the cutting comb, and means actuated by the operation of the handles for reciprocating the guard comb and the stationary cutting comb to cause these parts to cooperate to effect the cutting in the use of the instrument.

2. A shaving instrument comprising a pair of pivoted handles, a stationary cutting comb having a concave surface adapted to

be applied to the skin, a guard member having teeth which project materially beyond the teeth of the cutting comb, and means actuated by the operation of the handles for 5 reciprocating the guard comb on the stationary cutting comb to cause these parts to coöperate to effect the cutting in the use of the instrument.

3. A shaving instrument comprising a 10 pair of handles, a stationary cutting comb having a concave surface adapted to be applied to the skin, a guard comb the teeth of which project materially beyond the teeth of the cutting comb, a rib on one of the said 15 handles extending into a recess provided therefor in the said guard comb to guide

and determine the direction of the movement thereof, a projection on one of said handles extending into a recess provided therefor in the guard comb for reciprocating 20 the same by the movement of the said handles, and a pin for pivotally connecting the said handles and maintaining the said combs yieldingly in operative contact with one another.

25 In testimony whereof I have affixed my signature in presence of two witnesses.

HERMANN WERNER.
